UNITED STATES PATENT OFFICE.

EDWIN J. GOULD, OF BOULDER, COLORADO, ASSIGNOR OF ONE-FOURTH TO
JAMES A. WALKER, OF BOULDER, COLORADO.

COMPENSATING GEAR.

No. 845,409.

Specification of Letters Patent.

Patented Feb. 26, 1907.

Application filed September 1, 1906. Serial No. 332,983.

To all whom it may concern:

Be it known that I, EDWIN J. GOULD, a citizen of the United States, residing at Boulder, in the county of Boulder and State of Colorado, have invented a new and useful 5 Compensating Gear, of which the following is a specification.

This invention relates to compensating gear of the type set forth in my United States 10 application, Serial No. 297,343, filed January 2, 1906, and allowed April 27, 1906.

The objects of the invention are to improve and simplify the construction of such devices; furthermore, to increase their efficiency in operation and to decrease the expense attending their manufacture.

With the foregoing and other objects in view, which will appear as the description proceeds, the invention resides in the combination and arrangement of parts and in the details of construction hereinafter described and claimed.

In the accompanying drawings, forming part of this specification, Figure 1 is a side 25 elevation, partly in section, of a compensating gear constructed in accordance with the present invention; and Fig. 2 is a horizontal section.

Like reference-numerals indicate corresponding parts in the different figures of the drawings.

The reference-numeral 1 indicates a driving element, which preferably is in the nature of a hollow disk-shaped casing, as shown. 30 The driving element 1 is adapted to be rotated from any suitable source of power, (not shown,) so as to transmit its motion to the driven elements hereinafter described. The driving element 1 preferably is formed in each of its sides with a pair of diametrically 35 opposite radial slots 2, in which are slidably mounted pins or bolts 3. The driven elements 4 preferably are in the nature of oppositely-extending shafts having their inner ends arranged in close proximity to each other. The driven elements 4 in one embodiment of the invention can be connected with the drive-wheels of a motor-car, so that 40 said wheels will be individually driven from the driving element 1 in such manner that they can rotate at different speeds in turning curves. Each of the driven elements 4 inside the driving element or casing 1 is provided with a rigid eccentric 5, which is con-

nected, by means of a link 6, with the slidable pin 3 at one side of the driving element 1. Each of the driven elements 4 is also provided with a second rigid eccentric 7, which is disposed at a right angle with respect to the eccentric 5—that is to say, a line drawn through the long center of the eccentric 5 would be disposed at an angle of ninety degrees with respect to a line drawn through the long center of the eccentric 7. The second eccentric 7 is connected, by means of a link 8, to the slidable pin 3 on the side of the driving element opposite the pin with which the eccentric 5 is connected. It will be understood that each of the links 6 and 8 is formed at its inner end with a large eye 9 to surround the eccentric on the driven element 4 and at its outer end with a small eye 10 to surround the adjacent pin 3.

It is believed that the operation of the improved compensating gear will be understood from the foregoing description in connection with the drawings. The rotation of the driving element 1 is imparted through the slidable pins 3 and links 6 and 8 to the eccentrics 5 and 7 and driven elements 4. If for any reason one of the shafts or driven elements 4 should be retarded in its rotation—such, for example, as when a motor-car is rounding a curve—the eccentrics 5 and 7 of the element 4 which is retarded will cause the links 6 and 8 to shift their position, whereby the opposite driven element 4, which is not retarded, will have its rotation accelerated.

The improved compensating gear of this invention is strong, simple, durable, and inexpensive in construction, as well as thoroughly efficient in operation.

What is claimed is—

1. A compensating gear comprising a plurality of driven elements each provided with a pair of eccentrics disposed at right angles with respect to each other, and a driving element having slidable links connected with said eccentrics.

2. A compensating gear comprising a plurality of driven elements each provided with a pair of eccentrics disposed at right angles with respect to each other, a driving element having slots, and links connected at their inner ends with said eccentrics and having a slidable connection at their outer ends with the slots of said driving element.

3. A compensating gear comprising a plurality of driven elements each provided with a pair of eccentrics disposed at right angles with respect to each other, a driving element having slots, pins slidably mounted in the slots of said driving element, and links connected at their inner ends with said eccentrics and at their outer ends with said pins.
4. A compensating gear comprising a pair of driven elements consisting of shafts disposed end to end and each having a pair of eccentrics disposed at right angles with respect to each other, a drive element consisting of a disk-shaped casing surrounding said driven elements and eccentrics and being

formed with a plurality of diametrically opposite radial slots, pins slidably mounted in the slots of said driving element, and oppositely-extending pairs of links each having an eye at its inner end to receive one of said eccentrics and an eye at its outer end to engage one of said pins. 20

In testimony that I claim the foregoing as my own I have hereto affixed my signature in the presence of two witnesses.

EDWIN J. GOULD.
